CORD HOLDER FOR ELECTRIC IRONS

Martha C. Allen, Washington, Mo.

Application September 24, 1948, Serial No. 50,893

1 Claim. (Cl. 248—51)

1

This invention relates to cord holders for electric irons, and the main object of the invention is to provide a cord holder of this kind comprising an elongated rod of flexible steel or the like, the same having a clamp at its lower end for engaging an ironing board, a combination hinge and swivel joint for connecting the clamp with the rod, and whereby the rod may be conveniently folded down alongside the board for storage when not in use, and a slotted head of insulation material at the upper end of the rod for frictionally engaging the electric cord leading from the wall plug to the iron as positioned upon the ironing board.

Another object of the invention is to provide a form of clamp for attaching a rod-like ironing cord holder to an ironing board, the said clamp including a U-shaped clamping member for positioning over an edge of the ironing board, a screw-threaded bolt passed through the lower jaw of the U-shaped member and adapted to turn up against the ironing board for lockingly engaging same, a flat clamp engaging tab hinged onto the U-shaped clamping member, a rod engaging tab swivelled upon the outer free end of the clamp engaging tab, a flexible cord supporting rod extended from the rod engaging tab, a slotted cord engaging head of insulation material mounted at the outer free end of the flexible rod, and means embodied upon the clamping member and associated clamp engaging tab and rod engaging tab for releasably maintaining the elements to upright position when in use, while permitting them to be folded flatly to the ironing board when not in use.

With the stated objects in view, together with such other and additional objects and advantages as may appear from the specification, attention is directed to the accompanying drawing as embodying certain preferred structural forms and features of the invention, and wherein

Figure 1 is a perspective view of a form of the invention employing a relatively short and stiff cord supporting rod, attached at one side of an ironing board arranged to fold up into a wall case when not in use, the position of the device as folded down upon the board being indicated in dotted lines.

Figure 2 is a frontal elevation on an enlarged scale, of the device as shown in Figure 1, as re-

moved from the ironing board, with the elements positioned vertically.

Figure 3 is a side or edge view of the device as shown in Figure 2.

Figure 4 is a similar side view of the device as folded down flatly.

Figure 5 is a rear elevation of the device, showing the hinged, clamp engaging tab turned upwardly and the rod engaging tab turned downwardly edgewise.

Figure 6 is a side elevation of the device as used upon an individual or unattached form of ironing board, and employing an elongated, flexible cord supporting rod extended from a clamp attached at the rear end of the board, the elements being all positioned as ready for use and the cord plug shown raised as for insertion into an overhead socket.

Figure 7 is a similar side elevation showing the electric iron and flexible cord supporting rod as in actual use upon the ironing board, the cord supporting rod being flexed outwardly with the forward movement of the iron.

Figure 8 is a view similar to that of Figure 7, the cord plug being shown as inserted into a base-board socket and the cord itself shown as wound upwardly along the long and flexible cord supporting rod.

As shown in details in Figures 2, 3, 4, 5, the most important feature of this invention lies in the form of the ironing board clamp referred to generally at 3, and its associated, and hingedly and swivelly connected elements, whereby the cord supporting rod 4 may be raised either vertically over the ironing board 5, in operative position for use, as shown in Figures 1 and 6, or may be folded down flatly upon the board for storage when not in use, as indicated in dotted lines in Figure 1, and in full lines in Figures 4 and 5.

The broadly formed clamp 3 is made of spring sheet steel, U-shaped in contour and includes a broad back piece 3a, a broad lower jaw 3b, a broad upper jaw 3c, and a pair of upstanding ears or tabs 3d extended up from the lateral margins of the upper jaw 3c in spaced alignment. This clamp 3 may be stamped out of sheet metal and formed with reinforcing bosses or beads 3e pressed out along the back 3a and over the jaws 3b, 3c. Deep latch-grooves 3f are formed ver-

tically on the inner faces of the upstanding tabs $3d$ and extend out through the upper ends of these tabs. The lower jaw $3b$ is bored and tapped as at $3g$ for threadedly engaging a threaded clamping bolt 6 , provided with a handle $6e$, and whereby the clamp 3 may be seated over the side edge or end of the ironing board 5 , as illustrated in Figures 1 and 6, and firmly locked thereto by turning up the bolt 6 .

The ears or tabs $3d$ are bored through as at $3h$, and a headed draw-bolt or thumb bolt 7 is passed through these bores of the tabs. A thumb-nut $7a$ is seated upon the outer extended and threaded end of the bolt 7 .

A double-leaved clamp engaging tab 8 is provided, the same being stamped out of sheet metal and folded medially upon itself and rounded out at the bight to form a sleeve $8a$, whereby it is seated upon the draw-bolt 7 , with the leaves $8b$, $8c$, turned upwardly and adapted to seat at their lateral edges within the latch grooves $3f$ of the tabs $3d$ when the thumb nut $7a$ is tightened up sufficiently to draw the tabs inward against the edges of the tab 8 , thus releasably locking the tab 8 to upstanding, vertical position. One of the leaves, as $8c$, of the double leaved tab 8 , is formed at its upper and lateral margins with latch-grooves $8d$, $8e$, and a short draw-bolt 9 is passed transversely through the leaves, the outer threaded end of this bolt being fitted with a thumb nut $9a$, whereby the leaves $8b$, $8c$, may be tightened up together or loosed, as may be required in the operation of the device and as later explained. A flat and oblong rod engaging tab 10 is pivotally swivelled upon the bolt 9 and between the leaves $8b$, $8c$ of the tab 8 , by passing the bolt 9 through the apertured lower end of this tab 10 as it is positioned between the leaves. The tab 10 is formed with a medial bead or boss $10a$, adapted to align with and seat into either of the latch grooves $8d$ or $8e$ of the leaf $8c$ of the tab 8 , as the tab 10 is turned up vertically as shown in Figure 2, or is turned down laterally as shown in Figure 5. Rod engaging loops $10b$ are pressed up from the tab 10 in longitudinally spaced alignment, and the lower end of the cord supporting rod 4 is frictionally seated through these loops whereby this rod is thus operatively locked in position. The rod 4 is equipped at its upper end with a slotted head $4a$ of insulation material, the slot $4b$ of this rod being adapted to engage the conventional electric cord or conductor 11 , which connects the iron 12 with the wall socket 13 . This socket may be located, of course, at the ceiling of a room (not shown), as indicated in Figure 6, or at the floor as shown in Figure 8, or within a wall case 14 provided for receiving the foldable board 5 , as shown in Figure 1.

Where used in connection with a board foldable into a wall case 14 (Figure 1) a relatively short form of the cord supporting rod 4 is thought to be desirable, but for use upon the individual or unattached forms of ironing boards the long and flexible cord supporting rod, as shown in Figures 6, 7, 8, are more desirable, as these rods readily flex and bend according to the motions of the operator. As shown in Figure 8, the cord may be wound up and around the cord supporting rod when the socket 13 is positioned at the floor, thus keeping the cord free of the board 5 . Where the socket is overhead, that portion of the cord extending from the socket to the cord supporting rod is thus held up out of the way, and the portion of the cord extending from the rod to

the iron is frictionally gripped by the margins of the slot $4b$ of the insulation head $4a$, thus bringing into play the flexibility of the long form of cord supporting rod 4 , as shown in Figures 6 and 7.

In use, the rod 4 is raised to its vertical position by turning the clamp engaging tab 8 up until its edges align and fall into the latch grooves $3f$ of the tabs $3d$, after which the draw bolt 7 is tightened up for locking the ears or tabs $3d$ to the edges of the tab 8 for holding same in vertical position. Similarly, the rod 4 and connected tab 10 are then turned up vertically and the draw bolt 9 is tightened up for locking the bead or boss $10a$ into the latch groove $8d$ of the leaf $8c$ of the tab 8 , whereby all these elements are supported vertically in position for use. The light cord 11 is properly trained through the slot $4b$ of the insulated head $4a$ as carried by the rod 4 . When the work of ironing is completed, the cord 11 and iron 12 are removed, and the rod 4 is folded down laterally by first loosening the thumb nut $9a$ of the bolt 9 , after which the tab 8 is folded down by loosening the nut $7a$ of the bolt 7 . In this way the rod 4 may be folded down longitudinally upon the board 5 , regardless of whether it is mounted at the side of the board as in Figure 1, or at the end of the board as in Figure 6. The board 5 may then be stored away without removing the clamp 3 and attachments. This is a considerable advantage, since it saves time and guards against loss of any of the parts.

It is thought that the construction, use and operation of the device will be fully understood from the foregoing description, and while I have here shown and described a specific embodiment of the invention and structural features thereof, the same may be changed and modified in minor details as may be desired, within the scope of the claim.

I claim:

In a device of the kind described, an ironing board clamp of spring sheet metal, U-shaped in contour and formed with a broad back piece and lower and upper jaws and a pair of upstanding tabs extended up from the lateral margins of the upper jaw in spaced alignment, the said back piece and jaws being formed with reinforcing beads extended continuously along over the back and jaws, and there being deep latch-grooves formed and extended vertically on the inner faces of the upstanding tabs and out through the upper ends thereof, the said tabs being bored through in transverse alignment, a headed draw bolt passed through the bores of the tabs, a thumb-nut seated upon the outer extended end of the bolt, a double-leaved clamp engaging tab formed of sheet metal folded medially upon itself and rounded out at its bight as a sleeve for receiving the said draw-bolt, whereby the said double-leaved clamp engaging tab may be turned up vertically for releasably seating at their lateral edges in the latch grooves of the first mentioned upstanding tabs of the ironing board clamp when the said thumb-nut is tightened up, one of the leaves of the double-leaved clamp engaging tab being formed both at its upper and lateral margins with outwardly extended latch-grooves, a short draw-bolt passed transversely through the leaves of the said double-leaved clamp engaging tab, a thumb-nut seated upon the outer extended end of this bolt, a flat and oblong rod engaging tab pivotally swivelled upon the short draw bolt between the leaves of the double-leaved clamp tab, the latter being apertured through its lower

end for receiving said bolt, said rod engaging tab being formed with a medial boss adapted to align with and releasably seat in either of the latch grooves of the one leaf of the double-leaved clamp engaging tab as the rod engaging tab is turned up vertically or is turned down laterally, the said rod engaging tab being formed with rod engaging loops positioned thereon in longitudinally spaced alignment, a cord supporting rod seated at its lower end through said loops, and means for releasably securing the ironing board clamp upon a conventional elongated ironing board, whereby the said cord supporting rod may be turned down longitudinally upon the board whether the ironing board clamp is mounted upon

10

15

a side of the board or at an end thereof, and in either position may be turned up and supported vertically for use as may be desired.

MARTHA C. ALLEN.
